UNITED STATES PATENT OFFICE.

FRANK T. CABLE, OF NEW LONDON, CONNECTICUT, ASSIGNOR TO ELECTRIC BOAT COMPANY, A CORPORATION OF NEW JERSEY.

AIR-COMPRESSOR PISTON.

Original application filed June 30, 1920, Serial No. 393,066. Divided and this application filed February 10, 1923. Serial No. 618,257.

To all whom it may concern:

Be it known that I, FRANK T. CABLE, a citizen of the United States, residing at New London, in the county of New London, 5 State of Connecticut, have invented certain new and useful Improvements in Air-Compressor Pistons; and I do hereby declare the following to be a full, clear, and exact description of the invention, such as will 10 enable others skilled in the art to which it appertains to make and use the same.

This invention relates to two-stage air-compressors, and more particularly to the second-stage pistons used in such compressors.

According to the present practice the first and second stage pistons of two-stage air compressors are rigidly connected. This makes it necessary that the walls of the 20 first and second stage cylinders be exactly parallel and that the two pistons be in perfect alignment. In practice these conditions are difficult to meet, requiring as they do, exact and painstaking workmanship, and as a very slight deviation from 25 exact parallelism between the parts results in rapid wear, particularly in the second stage cylinder, it has been found difficult to maintain a tight fit between the second- 30 stage piston and its cylinder for more than short periods. The wear is taken up in large measure by the snap rings of the piston which must, in consequence, be renewed, some times as often as every two 35 or three months. This operation is difficult and costly as the compressor must be entirely dismantled and both pistons removed in order to gain access to the second-stage piston.

40 It is, therefore, clear that could some means be devised for minimizing this wear and obviating the necessity for such frequent replacements of the second-stage piston rings, a very substantial saving in time 45 and expense could be effected. It is broadly an object of the invention to accomplish this.

Going back to first causes, the origin of the trouble is found in the practical difficulty of getting perfect alignment between 50 the two cylinders, which are preferably integrally cast and must be machined with most exacting care. This difficulty has been overcome by the present invention

through the simple expedient of doing away 55 with the necessity for such exact alignment. To do this the two pistons are mounted for relative lateral and angular play, and thus automatically adjust themselves to any inaccuracies in the cylinder parallelism. In 60 doing this two important results are obtained; first, the wear is minimized, and, second, the need for scrupulous care in machining or grinding the cylinder bores is 65 done away with.

In order that the invention may be more clearly understood reference is had to the accompanying drawings disclosing one specific embodiment thereof.

In these drawings, Fig. 1 is a section 70 through a two-stage air-compressor equipped with relatively movable pistons designed in accordance with the present invention; and Fig. 2 is a section through the two pistons on an enlarged scale.

In the drawings, 1 represents a two-stage air-compressor. In this compressor, 2 represents the first-stage cylinder, 3 the second-stage cylinder, 4 the first-stage piston, and 5 the second-stage piston, this last being 80 provided with peripheral grooves 6 which fill with oil and serve as seal rings. The walls of the two cylinders are integral cast and form in effect one cylinder having two different bores. The two pistons are 85 connected by means of a bolt 7 which passes through the upper end of the piston 4, being keyed thereto at 8, and is provided at its upper end with a special nut 9 which bears upon an internal annular flange 10 90 situated near the upper end of piston 5. This nut is screwed upon threaded end 11 of bolt 7 and locked in position by means of tapered pin 12 which is screwed in the upper end of nut 9 and seated in a tapered and split socket 13 in the threaded end 11 of the bolt. Insertion of pin 12 into socket 13 expands threaded end 11 and fixes the nut 9 tightly in position. Piston 5 is provided at its upper end with a semi-spherical cap 14 locked in position by means of screw 15. Cylinder 3 is bushed by means of a removable sleeve or bushing 16 forming the wearing surface for the piston 5.

Play between the two pistons is permitted by clearance spaces 17, 18 and 19. In a case where alignment of the two cylinders happened to be particularly bad, piston 5 might

be twisted so far as to bind at the point where the edge of nut 9 bore upon flange 10. In order to prevent this the upper face of this flange is dished slightly as shown 5 at 20.

This application is a division of Serial No. 393,066, filed June 30, 1920.

I claim:

1. In a two-stage air-compressor the combination of a first-stage piston, a rod extending from the outer end thereof, a nut on the outer end of the rod, a hollow second-stage piston, and an annular flange therein, the nut on the rod bearing 10 against the annular flange to hold the second-stage piston in place on the first-stage piston, there being clearances between the rod and the second-stage piston permitting slight relative movement between the two 15 pistons.

2. In a two-stage air-compressor, the combination of a first-stage piston, a rod extending from the upper end thereof, a nut on the outer end of the rod, a hollow second-stage piston, and an annular flange therein, dished around its upper and inner periphery, the nut on the rod bearing 20 against the dished portion of the annular flange to hold the second-stage piston in place on the first-stage piston, there being clearances between the rod and the second-stage piston permitting slight relative movement between the two pistons.

3. In a two-stage air-compressor, the combination of a first-stage piston, a rod extending from the outer end thereof, a nut on the outer end of the rod, a hollow second-stage piston, an annular flange therein, the nut on the rod bearing against the annular 25 flange to hold the second-stage piston in place on the first-stage piston, there being clearances between the rod and the second-stage piston permitting slight relative movement between the two pistons, and a cap on 30 the second-stage piston covering the nut.

4. In a two-stage air-compressor, the com-

bination of a one-piece casting forming the walls of the first and second-stage cylinders in substantial alignment, first and second-stage pistons mounted to reciprocate within 50 their respective cylinders, and means connecting the two pistons permitting slight unrestrained combined relative lateral and angular movement between them to compensate for inaccuracies in the alignment. 55

5. In a two-stage air-compressor, the combination of a one-piece casting forming the walls of the first and second-stage cylinders in substantial alignment, first and second-stage pistons mounted to reciprocate within 60 their respective cylinders, said pistons abutting against one another and being provided with a connecting rod loosely connected at each end to one of the pistons so as to permit slight unrestrained relative 65 movement between them to compensate for inaccuracies in the alignment of the pistons.

6. In a two-stage air compressor the combination of a first-stage piston, a rod extending from the outer end thereof, a hollow second-stage piston having an annular flange therein, means on the rod bearing 70 against the annular flange to hold the second-stage piston in place on the first-stage piston, there being a clearance between the 75 rod and the flange permitting slight relative movement between the two pistons.

7. In a two-stage air-compressor the combination of a first-stage piston, a rod extending from the outer end thereof, a nut on the outer end of the rod, a hollow second-stage piston, and an annular flange therein, the nut on the rod bearing against the annular flange to hold the second-stage piston in place on the first-stage piston, there being 80 a clearance between the inner end of the rod and the second-stage piston permitting slight relative movement between the two pistons. 85

In testimony whereof I affix my signature.

FRANK T. CABLE.
